(57) **CLAIM**

The ornamental design for earphones, as shown and described.

DESCRIPTION

FIG. 1 is a perspective view of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 2. The dash-dash broken lines in the drawings depict portions of the earphones that form no part of the claimed design. The dot-dash broken lines encircling portions of the earphones in FIGS. 1 and 2 and illustrated in enlarged views of FIGS. 9 and 10 form no part of the claimed design.

The earphones are shown with a symbolic break in the earphone cord length. The appearance of any portions of the article between the break lines forms no part of the claimed design.
